UNITED STATES PATENT OFFICE.

ELMER E. WICKERSHAM, OF STOCKTON, CALIFORNIA.

AIR CLEANER.

1,407,968.

Specification of Letters Patent. Patented Feb. 28, 1922.

Application filed June 1, 1918. Serial No. 237,775.

To all whom it may concern:

Be it known that I, ELMER E. WICKERSHAM, a citizen of the United States, residing at Stockton, in the county of San Joaquin and State of California, have invented a new and useful Improvement in Air Cleaners, of which the following is a specification.

This invention relates to a carbureter for the production of gaseous fuel, and particularly pertains to air cleaning means therefor.

It has been found in practice that the air contained within the gaseous fuel which is delivered to the cylinders of internal combustion engines usually is laden with solid particles of carbonaceous, mineral or gritty material, which is detrimental to the operation of the engine, in some cases forming a carbon deposit within the cylinder, while in other cases a gritty substance which objectionally scores the cylinders and pistons. This is especially true of explosive engines which are used in connection with trucks, tractors and various agricultural implements, as the atmosphere during the operation of these vehicles will be particularly charged with foreign material and will therefore increase the deposit of solid matter within the cylinders. It is the principle object of this invention, therefore, to provide means acting in co-operation with the carbureter to thoroughly clean the air utilized in forming the gaseous fuel and to rid it of all solid material. Due to the fact that the air is drawn to the carbureter by the suction of the engine it is essential that this air is not restricted in its flow, as the power of the engine will be thus decreased and a further object of this invention is to provide an air cleaning device which is devoid of straining-screens or other obstructions which would impede the ample flow of air as required by the engine.

The present invention contemplates the use of concentric telescoping casing members having their side wall spaced in relation to each other to form an unrestricted air inlet passageway and having their lower ends disposed in relation to each other to provide a sealed dead air space into which the solid particles carried by the air may be thrown as the air flows downwardly along the annular passageway and thereafter is diverted upwardly through a central outlet opening through the inner casing, thus di-

verting the solid particles from the path of the air as they are influenced by the action of inertia and gravity.

The invention is illustrated by way of example in the accompanying drawing in which:

Figure 1 is a view in side elevation illustrating one form of the device here shown as incorporated within a carbureter operatively connected to the intake manifold of an internal combustion engine.

Fig. 2 is a view in vertical section as seen through the device disclosed in Figure 1 and particularly illustrates the dust separating elements.

Fig. 3 is a view in horizontal section as seen on the line 3—3 in Fig. 2 and discloses the formation of the dust separator and correlation in its vital parts.

Fig. 4 is an enlarged view in vertical section illustrating a modified form of the invention disclosing it as having a plurality of dust removing units arranged without reference to a carbureter construction.

Referring more particularly to the drawings 10 indicates an internal combustion engine fitted with an intake manifold 11 adapted to conduct a gaseous fuel to the engine cylinders from a carbureter 12. In the present instance the carbureter is combined in its construction with a device for removing dust and other solid particles from the air which later unites with the liquid fuel in the carbureter forming a clean explosive gas. This structure as particularly disclosed in Fig. 2 comprises an outer casing 13 which is substantially elliptical in horizontal section and is adapted to enclose a float chamber 14. The float chamber is preferably cast integral with the case and extends perpendicularly from its bottom wall. This chamber terminates at a point midway the height of the casing and is there covered by a suitable closure 15. A float member 16 is contained within the chamber and controls a valve 17 adapted to regulate the flow of liquid fuel from a supply conduit to the chamber. As here disclosed an upwardly extending stem 18 projects downwardly through the cover and its lower end normally submerged within the liquid fuel. The upper end of this stem communicates with a metering nozzle 19 within which the liquid fuel is gasified as it unites with the air and passes therethrough.

The nozzle 19 is mounted within a casing

20 by which the top of the case 13 is entirely closed. This cover member carries a housing for valve mechanisms 21 and 22, as well as a mounting for a butterfly valve 23
5 which constitutes the throttle mechanism of the carbureter. Projecting downwardly from the main wall of the cover 20 is a continuous baffle wall 24 which substantially corresponds in sectional contour to the wall of
10 the case 13 and which is spaced a distance therefrom to form a circulating passageway 25 between the upper portion of the casing wall and the baffle wall. The lower end of this baffle wall terminates on a line corresponding substantially to the top line of the
15 float chamber and thus combines therewith to form an inlet passageway around the top of the float chamber and into the space thereabove, which space is partially occupied by
20 the nozzle 19. A horizontally and outwardly extending flange 26 is formed entirely around the outer periphery of the baffle wall 24. This wall corresponds in contour to the inner surface of the case 13 and is spaced a
25 short distance therefrom to form an air passageway through which all of the air entering the carbureter must pass. Flange 26 is located with its outer face in substantial alignment with the lower wall of air intake
30 port 27 through which all the air passing to the carbureter is admitted.

The valve members 21 and 22 are adapted to admit air from the chamber surrounded by the baffle wall 24 to a by-pass chamber
35 which is in direct communication with the carbureter outlet port. These valve members are normally held upon their seats by expansion springs 29, which may be optionally tensioned by means of adjusting nuts 30.
40 Due to this construction the acceleration of the engine will cause them to be elevated and insure that a lean mixture will be produced by the carbureter on high speeds and in an automatic manner.

45 In the form of the device shown in Fig. 4, the carbureter construction has been eliminated and the dust separator has been formed to be used as an accessory to any suitable carbureter. In this form a horizontal extending intake chamber 31 is provided above which a parallel outlet chamber 32 is mounted. These two chambers communicate with each other at given points along their lengths and thus insure that the air passing to the carbureter will not be restricted in its flow.
50 The lower casing member 31 is provided with a series of openings in its lower wall and here shown as four in number. These openings are normally closed by means of cylindrical casing members or cups 34, which may be of any desired length and which are provided as receptacles for the foreign materials eliminated from air passing into the carbureter. The separation of this material
55 is effected within the present device by the

provision of a cylindrical tubular 35, which is carried by the housing and form continuations of communicating passageway between the upper and lower chambers 32 and 31. These stems extend downwardly through
70 the openings in the lower case and are spaced with their side walls an equal distance from the side walls of the cups, in this manner combining therewith to form annular passage ways leading from the lower casing to
75 the central opening through the stems.

It will be observed by comparison of the two structures here disclosed that the air cleaning features are the same, that is, both of them provide means for directing the air
80 downwardly and thereafter causing it to change its direction of travel abruptly to an upwardly direction so that considerable inertia will be imparted to the solid particles of the air, which force will be assisted
85 by gravity to carry the particles out of the range of influence of the air and into the dead air space at the bottom of the casings. Thus this solid matter will be deposited
90 within the casing 13 or the cups 34, where it may accumulate in the operation of the device first described.

In the operation of the first described device the suction action of the engine will draw air in through the manifold 11 and the carbureter initially through the air inlet port 27 at each pulsation. This incoming air will circulate around and within the chamber 25 and will pass downwardly around the horizontally extending flange 26
100 into the lower portion of the case 13. Due to the strength of the suction action the flow of air will take place around the marginal edge of the baffle wall 24 without materially affecting the air at the bottom of the case.
105 The air current will pass rapidly around the baffle wall and into the space enclosed thereby to thereafter find its way through the nozzle 19. After reaching this point it will unite with liquid fuel and form an explosive gas, passing outwardly to the engine as controlled by the throttle valve 23. It will be readily observed that the violent action of the air as it passes around the lower marginal edge of the baffle wall will cause the solid particles in suspension therein to be thrown off at a tangent to the current and in the present instance into the dead air space at the bottom of the casing. The effective area of the circulatory chambers and
110 passage ways are so proportioned as to accommodate the required volume of air without restriction of its flow.

115 The second form of the invention operates in substantially the same manner as above described. In this instance, however, a sufficient volume of air may be handled for engines of large displacement, as there are a plurality of cleaning elements provided, acting simultaneously. The air will pass in
120
125
130

through the opposite ends of the case 31 and then downwardly through the various openings into the lower cups, where it will be directed upwardly around the projecting ends of the stems 35. The action of these stems will be the same as the action of the baffle member 24 previously referred to and will abruptly change the direction of the flow of air to allow the solid particles to settle within the cup members 34. When a sufficient quantity of foreign material has been deposited within the casing 13 or the cups 34, the structures may be cleaned, in the former instance by removing the cover member 20 and in the latter by removing the individual cups 34.

It will thus be seen that the devices here disclosed embody simple, thoroughly effective means for eliminating solid particles from the air utilized in forming a gaseous fuel, by depositing the solids in a dead air space and without restricting the flow of the air, thereby allowing the carburetor to function properly as demanded by the engine.

While I have shown the form of my device as now known to be, it will be evident that various changes in the construction, combination and arrangement of parts may be made by those skilled in the art without departing from the spirit of the invention as claimed.

Having thus described my invention, what I claim and desire to secure by Letters Patent is—

1. In a carburetor, a mixing chamber, an air cleaner comprising an inner casing surrounding the mixing chamber, an outer casing forming an annular inlet air passage-way between the casing walls and means whereby the pulsations of a suction device will cause air to flow through said passage-way and the inner casing in a manner to effect the separation of solid matter from the air without restricting its flow, said outer casing being extended far enough below the inner casing to deposit the separated solid matter away from the influence of the air flow.

50 2. In a carburetor, a mixing chamber, an

air inlet for the mixing chamber comprising an inner casing open at its bottom, an outer casing extending below the first named casing and there around to form a sealed dead air collecting chamber, a top closure for said 55 casing provided with a discharge opening and an air passageway between said inner and outer casings, whereby air will be allowed to flow from the surrounding atmosphere through the passageway and to the 60 discharge opening in a manner to separate the solid particles from said flowing air and to deposit them within said dead air chamber.

3. In a carburetor, a mixing chamber, an 65 air inlet for the mixing chamber comprising an inner casing open at the bottom, a second outer casing extending below the first named casing and forming a sealed dead air collecting chamber, a top closure for said 70 casings provided with a discharge opening, an air circulating passageway between said casings and opened to the outside air beneath and adjacent said top closure and discharging within said outer casing near the 75 bottom of the first named casing and there around, for causing the current of admitted air to circulate above the dead air collecting chamber.

4. In a carburetor, a mixing chamber for 80 fuel and air, an inner casing surrounding the same and extending below, an outer casing surrounding the inner casing, said outer casing being provided with air inlet passageways to cause the air admitted to the 85 mixing chamber to pass downwardly between the inner and outer casings, and a dead air collecting chamber disposed below said inner and outer casings to receive the solid particles separated from the air by 90 the passage of the latter around the lower end of the inner casing.

In testimony whereof I have hereunto set my hand in the presence of two subscribing witnesses.

ELMER E. WICKERSHAM.
